UNITED STATES PATENT OFFICE.

GEORGE BRAND, OF BROOKLYN, NEW YORK.

DESIGN FOR A BEDSTEAD-RAIL MEMBER.

SPECIFICATION forming part of Design No. 29,002, dated July 5, 1898.

Application filed October 22, 1896. Serial No. 609,767. Term of patent 7 years.

To all whom it may concern:

Be it known that I, GEORGE BRAND, a citizen of the United States, and a resident of Brooklyn, in the county of Kings and State 5 of New York, have produced and invented a certain new and useful Design for a Bedstead-Rail Member, of which the following is a specification.

In the accompanying drawings, which form 10 a part of this specification, there is illustrated in Figure 1 in perspective a bedstead-rail member embodying the invention, and in the same manner in Fig. 2 the essential features are illustrated on an enlarged scale.

15 The essential features of the design reside in the configuration of the coupling end of the member, whereon is borne the T-head. Said coupling end has a flat face B, from which projects, substantially at right angles thereto,

a vertical neck, as indicated at D. This neck 20 is terminated by a vertically-disposed head E, which with said neck constitutes the T-head. The outer wall of the head is substantially vertical and substantially cylindrical, while the inner walls thereof, F F', are plane and 25 stand at an oblique angle to the sides of neck D and are inclined vertically toward the face B.

I claim as my invention—

The design for a bedstead-rail member substantially as shown and described.

Signed at New York, in the county of New York and State of New York, this 20th day of October, A. D. 1896.

GEORGE BRAND.
